POWER-OPERATED PRINTING MACHINE

Commodore D. Ryan and Edward P. Drake, Los Angeles, Calif., assignors to National Postal Meter Company, Inc., Rochester, N. Y., a corporation of Delaware

Application February 5, 1941, Serial No. 377,418

1 Claim. (Cl. 101—235)

This invention relates generally to printing machines, and more particularly to electrically operated postage printing machines for printing postage on envelopes, tapes, and the like.

A general object of the invention is to provide an electrically operated printing machine of the type referred to, which is relatively simple in construction, reliable and trouble-free in operation, and readily adaptable to handle a wide variety of work.

Another object is to provide an electrically operated machine that is readily adjustable for either steady operation, with the motor running continuously, or for intermittent work, in which the motor is automatically started at the beginning of each stamping operation and stopped at the end thereof. The first method of operation is advantageous when handling large quantities of mail, whereas the second method has advantages when relatively small amounts of mail are to be handled at any one time.

A more specific object is to provide an electrically operated postage printing machine that is automatically started in response to insertion into the machine of an envelope to be stamped, and that has a particularly sensitive control mechanism capable of being actuated by very thin and flexible envelopes.

Another object is to provide a power-operated printing machine that can be conditioned either to print postage on envelopes fed through the machine, or to print on a continuous tape and deliver the printed tape from the machine, and has suitable interlocks for insuring the proper operation of the machine in both conditions of adjustment, without the attention of a skilled operator.

Another object of the invention is to provide an electrically operated postage printing machine having a particularly simple and effective mechanism for insuring the complete discharge of printed envelopes from the machine.

Other more specific objects and features of the invention will become apparent from the detail description which follows of a particular embodiment of the invention, as illustrated in the drawings.

In the drawings:

Fig. 1 is a view of a machine in accordance with the invention, as viewed from above, some portions being shown in plan, and others in section;

Fig. 2 is a vertical section taken substantially in the plane 2—2 of Fig. 1;

Fig. 3 is a vertical section taken substantially in the plane 3—3 of Figs. 1 and 2;

Fig. 4 is a detail section taken along the curved line 4—4 of Fig. 3;

Fig. 5 is a vertical section taken substantially in the plane 5—5 of Figs. 1 and 2;

Fig. 6 is a horizontal section, taken along the line 6—6 of Fig. 5;

Fig. 7 is a section similar to Fig. 5, but showing the mechanism in a different operative position;

Fig. 8 is a detail vertical section, taken in the plane 8—8 of Fig. 7;

Fig. 9 is a detail vertical section, taken in the plane 9—9 of Figs. 1 and 2;

Fig. 10 is a detail horizontal section, taken in the plane 10—10 of Fig. 9;

Fig. 11 is a detail vertical section, taken in the plane 11—11 of Figs. 1 and 2;

Fig. 12 is a schematic wiring diagram of the electrical circuit of the machine;

Fig. 13 is a vertical section, taken substantially along the line 13—13 of Fig. 1;

Figs. 14 and 15 are fragmental views taken in the same plane as Fig. 13, showing different stages of operation in printing on envelopes;

Figs. 16, 17, 18, 19 and 20 are sectional views taken in the same plane as Fig. 13, but showing the tape-printing mechanism in different positions of operation;

Fig. 21 is a vertical section taken substantially in the plane 21—21 of Fig. 13, with certain tension springs eliminated;

Fig. 22 is a horizontal section, taken substantially in the plane 22—22 of Fig. 14, said tension springs also being eliminated in this view to clarify the view;

Fig. 23 is a horizontal section taken in the plane 23—23 of Fig. 18, with certain tension springs also eliminated from this figure to clarify the view; and

Fig. 24 is a perspective view of a complete machine in accordance with the invention, with a postage meter attached, ready for operation.

Referring, first, to the perspective view of Fig. 24, the machine of the present invention comprises a power unit 25 adapted to support and operate in conjunction with a postage meter 26. The postage meter 26 may be of the type described in the copending application of Frank P. Sager, Ernest R. Bergmark, Commodore D. Ryan and Herschel L. Atherton, Serial No. 332,305, filed April 29, 1940, for Mail treating machine, and its details do not constitute a part of the present invention. Suffice it to say that the meter has:

55 (1) A coupling member adapted to couple to

and be driven by a driving coupling member on the powerplant 25;

(2) A downwardly extending locking pin which actuates certain interlock mechanisms in the powerplant;

(3) Locking pins cooperating with locking elements in the powerplant for locking the postage printing meter in operative position on the powerplant;

(4) A printing head within a housing indicated at 27 in Fig. 24.

The coupling member on the postage meter 26 is indicated at 28 in Fig. 2, which shows only the rear end of the postage meter. This coupling 28 cooperates with a driving coupling 29, which appears in Fig. 2 and also in Fig. 1 of the drawings.

The postage meter is not shown in Fig. 1, but the locking and interlocking pins projecting downwardly therefrom are shown in section. Thus the locking pins are indicated at 30 and in the interlock pin at 31. There also projects downwardly from the postage meter a positioning pin 32 which is adapted to be engaged by a locking lever 33 in the powerplant when a locking handle 34 is swung into locking position. The details of operation of the locking pins 30 and the positioning pin 32 and the cooperating elements in the powerplant are not essential to an understanding of the present invention, and will not be described herein. They are described in detail in the aforementioned application Serial No. 332,305, to Sager et al., previously referred to.

For the purpose of the present invention, it is only necessary to know that the postage meter includes, positioned within the housing 27, a rotary printing head 35 (indicated schematically in Fig. 13), which is rotated by the coupling 28 to carry a printing face 36 thereon into contact with an envelope 37 moving through the machine, as shown in Fig. 15. It will be observed from Fig. 15 that the envelope 37 is supported against the printing face 36 of the printing head by a rotary platen 38 which platen is rotated in synchronism with the printing head 35 of the postage meter by the mechanism of the present invention.

Driving mechanism

The platen 38 is mounted on a shaft 39 (Fig. 1) which is journaled in bearings 40 and 41 in the side walls 42 and 43, respectively, of a platen carriage 44. At its rear end (the right end in Fig. 1), the shaft 39 is connected by a universal joint 45 to the front end of a connector shaft 46, the rear end of which is connected by a universal joint 47 (Fig. 2) to the front end of a platen drive shaft 48. This platen drive shaft 48 is supported in bearings 49 and 50 in vertical walls 51 and 52, respectively, of the powerplant, and has pinned thereto a gear 53 which permanently meshes with a gear 54 of the same size on a meter drive shaft 55, which is positioned above the platen drive shaft 48 and supported by bearings 56 and 57, respectively, in the two vertical walls 51 and 52. The forward end of the meter drive shaft 55 carries the driving coupling member 29 which engages the driven coupling member 28 of the postage meter. It will be apparent from the foregoing description that the printing platen and the printing head are constrained to rotate in unison with each other at the same speed.

The shaft 55 and the shaft 48 are driven through a transmission and a clutch mechanism from an electric motor 58 (Fig. 1), this motor be-

ing mounted below the platform 59 which supports the postage meter. The motor shaft 60 (Fig. 2) is connected to the left end of a shaft 62 which is journaled at its right end in a bearing 63 in the wall 52. A suitable aperture 64 (Fig. 3) is provided in the wall 51 through which the coupling 61 extends.

Pinned to the shaft 62 (Fig. 2) are two V-pulleys 65 and 66, respectively. The pulley 66 (Fig. 3) is coupled, by a crossed belt 67, to a pulley 68 pinned to the shaft 69. This shaft 69 (Fig. 1) is supported at its right end by a bearing 70 in the wall plate 52, extends nearly the full length of the machine, and is rotatably supported near its left end in a bearing 71 mounted in an oscillatable supporting arm 72. On its extreme forward end, beyond the bearing 71, the shaft 69 mounts a rubber faced ejector roller 73 which functions to eject envelopes from the machine after they have been printed.

The ejector roller 73 is swung downward out of the way when the machine is conditioned to print postage on tape, instead of on envelopes. This is accomplished by rocking the arm 72 downward about a shaft 74 (on which it is mounted by a bearing 75), the shaft 69 swinging simultaneously in the bearing 70, which is of the universal type similar to bearing 57 shown in detail in Fig. 2. The details of construction of the ejector roller 73 and its adjustable supporting arm 72 do not constitute a part of the present invention; they are fully described in our copending application, Serial No. 369,570, filed December 11, 1940, to which reference is made.

It will be observed from the foregoing description that the shaft 60 of the motor (Fig. 2) is permanently coupled to the pulley 66 which is in turn coupled by the belt 67 to the pulley 68 (Fig. 1) on the shaft driving the ejector roller 73, so that the ejector roller rotates with the electric motor at all times. In this way the inertia of the electric motor is utilized to continue the rotation of the ejector roller after the printing head and printing platen have stopped, as will appear more clearly following the description of the driving mechanism for the printing head and platen.

Referring, again, to Fig. 2, the pulley 65 is coupled by a V-belt 76 to a large V-pulley 77, which is journaled for free rotation on the shaft 48. The pulley 77 is integral with a small pulley 78 which in turn is coupled by a V-belt 79 to a large pulley 80 journaled for free rotation on the shaft 55, which drives the postage meter. This pulley 80 is adapted to be selectively coupled to the shaft 55 by a clutch mechanism next to be described.

The clutch mechanism includes a driving ratchet hub 81 which is formed integrally with the pulley 80 and has ratchet teeth 82 (Fig. 5) which are adapted, under certain conditions of operation to be described later, to be engaged by any one of three pawls 83. All of these pawls are similarly pivotally mounted on pins 84, which extend between a pair of discs 85 and 85a, and are urged toward the ratchet teeth 82 by torsion springs 86. When one of the pawls 83 is in engagement with the ratchet hub 81 and the latter is being rotated, the discs 85 and 85a are rotated, and they in turn rotate the shaft 55 through a flexible coupling 87 (Fig. 2), now to be described.

This flexible coupling 87 includes a hub 88 to which the disc 85 is secured. The hub 88 is in turn secured to a three-armed spider 89 (Figs.

9, 10), which spider is secured by three bolts 90 to a flexible ring 91. The ring 91 is also secured by three bolts 92, symmetrically spaced circumferentially with respect to the bolts 90, to the gear 54. Therefore the gear 54 (Fig. 2) is coupled through the flexible ring 91 to the clutch disc 85 and rotates with it, but the ring 91 is capable of yielding slightly and thereby cushions the shock incident to starting and stopping.

To facilitate adjustment of the rotary position of the shaft 55 with respect to the clutch disc 85, the arms of the spider 89 are provided with arcuate slots 93 (Fig. 9) to receive the bolts 90, so that by loosening the bolts the spider 89 can be adjusted angularly to a desired position with respect to the gear 54 (which is pinned to the shaft 55), and then locked in that position by tightening the bolts 90. To maintain the bolts 90 in proper alignment during adjustment operations, a floating spider 94 (Fig. 10) is provided immediately in front of the spider 89. This spider 94 fits freely on the shaft 55 and differs from the spider 89 in having round holes tightly fitting the bolts 90, instead of having arcuate slots.

The important function of the floating spider 94 is to maintain the three bolts 90 substantially parallel with each other when they are loosened for adjustment and thereby prevent any possibility of the flexible ring 91 being distorted while making the adjustment. As the result of distortion, the driving torque transmitted by the ring might be localized in one portion of the ring, thereby reducing its life and also producing unbalanced radial forces between the associated parts, and thereby causing premature wear. Nuts 90a are provided on the bolts 90 between the floating spider 94 and the flexible ring 91 to space those parts axially from each other and to permit the bolts to remain in firm clamping engagement with the ring 91 during adjustment of the spider 89.

Referring to Figs. 2 and 5, it will be noted from the description already given, that the ratchet hub 81 constitutes the driving member of the clutch and the disc 85 mounting the pawls 83 constitutes the driven member. Normally the pawls 83 are maintained clear of the ratchet teeth 82 so that the clutch is disengaged. The mechanism for disengaging the pawls includes a clutch lever 95, which is positioned between the disc 85 and the ratchet hub 81 and is fulcrumed on a pin 96 which extends between the discs 85 and 85a. The lever 95 has an aperture 95a substantially larger than the shaft 55 through which the latter passes so that the lever can oscillate through an appreciable angle about the pin 96 without interfering with the shaft 55.

As shown in Fig. 5, the clutch lever 95 is in extreme counter-clockwise position with respect to the disc 85, in which position three shoulders 97 on the clutch lever 95 engage the three respective pawls 83 and hold them clear of the ratchet teeth 82. The clutch lever 95 is normally held in the disengaging position shown in Fig. 5, against the force exerted by a tension spring 98, by a hook 101 on an upwardly extending arm 100 of a four-arm latch lever 99, the hook engaging a shoulder on the free end of the clutch lever 95. The latch lever 99 (Fig. 8) has a hub 102 which is rotatably supported on a bolt 103, the latter being supported at its opposite ends by shock absorbing mountings 104 in the walls 105 and 106 of a U-shaped bracket 107 which is secured to the base plate 108 of the machine. The

latch lever 99 is normally held in clockwise position, in which the hook 101 engages the clutch lever 95, by a tension spring 109 stretched between a horizontally extending arm 110 of the latch lever 99 and a switch rocker plate 111, the latter being oscillatably supported by a screw 112 on the wall member 105. The spring 109 therefore not only urges the latch lever 99 clockwise, but urges the switch rocker plate 111 counter-clockwise.

The clockwise movement of the latch lever 99 in response to the force of the spring 109 is limited by movement of a downwardly extending arm 113 thereon against a resilient stop member 114. The latter is supported on the upper end of a leaf spring 115 which is secured at its lower end to the bracket member 107. The exact position of the stop member 114 can be adjusted by a screw 116. The switch rocker plate 111 has a shoulder 117 which bears against the rear edge of the arm 113 so that it follows the movement of the arm 113. The switch rocker plate 111 has clips 118 (Fig. 8) for supporting a mercury switch 119 having a pair of leads 120 and 121, which connect the mercury switch in series with the motor so that it can control the operation of the motor. When the switch rocker plate 111 and the latch lever 99 are in the position shown in Fig. 5, the switch is open and the clutch is disengaged.

In addition to holding the clutch lever 95 in position to disengage the clutch, the hook 101 on the latch lever arm 100 also engages a shoulder 122 (shown in dotted lines in Fig. 7) on the disc 85 to stop the disc in a predetermined position.

The disc 85 (Fig. 5) is rotating rapidly at the time it is stopped by engagement of the shoulder 122 against the hook 101 and tends to rebound. Means is provided to prevent such rebound. It includes a pawl 123 (Fig. 11) pivotally supported at 124 on the gear 54 for rotation therewith. The nose 125 of the pawl is urged outwardly by a leaf spring 126 into a position normally determined by engagement of a pin 127 projecting from the side of the pawl, with the edge of an aperture 128 in the gear 54. However, as the gear 54 approaches its normal position of rest, (which is shown in Fig. 11) the nose 125 of the pawl encounters an inclined surface on a stop member 129 secured to the wall 51, and is deflected against the force of the leaf spring 126 as the gear moves into final position, at which time the nose of the pawl snaps past a shoulder at the upper end of the stop 129 (as shown in Fig. 11), and prevents any reverse movement of the gear. The stop member 129 is adjustably supported on the wall 51 by bolts 130 which extend through a slot 131 in the stop member.

The latch lever 99 (Fig. 5) is electrically operated, and to this end it has a horizontal arm 132 which is connected by a link 133 to the plunger 134 of a solenoid 135, the latter being mounted on the bracket 107.

When the solenoid 135 is energized, it pulls the plunger 134 downward, rocking the latch lever 99 counter-clockwise to carry the hook 101 clear of the shoulder 122 on the clutch lever 95. At the same time the switch plate 119 is rocked clockwise to start the motor, by the downwardly extending arm 113 of the latch lever 99, all as shown in Fig. 7.

Immediately upon disengagement of the hook 101, from the lever 95, the latter is rocked up-

ward against a stop 136 by its tension spring 98, carrying the shoulders 97 clear of the pawls 83 and permitting them to be moved by their torsion springs against the ratchet teeth 82, so that one of the ratchet teeth 82 engages one of the pawls 83 to rotate the disc 85 and the shaft 55. It will be noted that the disc 85 is free to rotate at this time because the hook 101 is held clear of the shoulder 122 on the disc 85.

The spacing of the three pawls 83 is such that only one of the pawls will engage one of the ratchet teeth, and the greatest distance that the ratchet hub can rotate before engaging one of the pawls 83 is one-third of the distance between adjacent teeth. This permits the use of relatively coarse teeth on the ratchet member to provide a positive driving engagement between the pawl and the ratchet teeth, while at the same time insuring prompt engagement of the clutch.

The solenoid 135 is energized only momentarily so that well before the disc 85 has completed a revolution the latch lever 99 has been returned clockwise by the spring 109 to its normal position, as shown in Fig. 5. Therefore as the disc 85 moves into neutral position, the end of the clutch lever 95 is engaged by the hook 101 and rocked counter-clockwise relative to the disc 85 to disengage the pawls 83 from driven engagement with the ratchet hub 81. Furthermore the shoulder 122 on the disc 85 also engages the hook 101 on the latch lever immediately following the disengagement of the pawls 83, to positively stop the disc in the normal position of rest.

As has been previously indicated, the machine is designed to start and stop the motor at the beginning and end of each cycle of operation. Furthermore, it will be recalled that the motor was started in response to energization of the solenoid 135 by the rocking movement of the latch lever 99, the lower arm 113 of which rocks the switch plate 111 clockwise into the position shown in Fig. 7. However, since the latch lever 99 is rocked only momentarily and returns to normal position prior to completion of the cycle of operation, it is necessary to take the switch plate 111 out of the control of the latch lever 99 following its movement into the position shown in Fig. 7, until the end of the cycle. To accomplish this result, the switch plate 111 is provided with a cam roller 137 which cooperates with a cam 138 on the shaft 48, which shaft is geared to and rotates at the same speed as the shaft 55. With the apparatus in normal, or neutral, position, the roller 137 (Fig. 5) rests in a notch 139 in the cam 138. However, immediately following the engagement of the clutch to rotate the shafts 55 and 48, the notch 139 is carried clear of the roller 137 so that when the solenoid 135 is de-energized and the latch lever 99 is rocked back into the normal position shown in Fig. 5, the roller 137 rides on the rim of the cam 138, and the switch plate 111 is prevented from being returned to normal position by the tension spring 109 until the cycle is completed, at which time the roller 137 again drops into the notch 139, actuating the switch to open the circuit automatically.

When the solenoid 135 is energized, it snaps the latch lever 99 and the switch plate 111 sharply, and tends to kick the switch plate substantially past its closed position. To prevent over-travel of the switch plate 111, a bumper 140 is provided on the wall 107, which bumper is in the

path of a stop arm 141 on the switch plate 111. The bumper 140 is made of yieldable material, such as rubberized fabric, to reduce the noise of impact.

It is desirable that the V-pulleys 77 and 80 be of the variable diameter type to permit ready adjustment of the belt tension and a feature of the present invention is a simple and effective variable diameter V-pulley construction. Thus, as shown in Figs. 2 and 3, the pulley 80 comprises two sheet metal sections 142 and 143, respectively, which are adjustable axially with respect to each other to vary the effective diameter of the pulley. The inner section 142 of the pulley is rigidly secured to the hub 81 as by welding 144. The outer section 143 is slidably mounted on a reduced extension 145 of the hub 81, and is secured to the section 142 by three bolts 146 (Figs. 3 and 4). These bolts extend through slots 147 formed in small areas 148 of the pulley sections, which areas are pressed at an angle to the main bodies of the flanges. It will be obvious from inspection of Figs. 3 and 4 that by loosening the bolts 146 and rotating the free pulley section 143 with respect to the section 142, the sections can be separated to a desired extent and secured in the separated position by re-tightening the bolts 146.

An interlock is provided to prevent actuation of the latch lever 99 (Fig. 5) by the solenoid 135, unless the postage meter is properly secured to the power unit, and is in operable condition. This interlock includes a latch 149 which cooperates with the horizontal arm 110 of the latch lever 99 and is controlled by the interlock pin 31 (Fig. 1) that projects from the bottom of the postage meter. When the postage meter is in operative condition the pin 31 projects downwardly from the case of the meter a predetermined distance so that if the meter is properly secured in position upon the meter-supporting platform 59, it depresses the forward end (the left end in Fig. 1) of a lever 150. This lever 150 is fulcrumed by a screw 151 to a bracket 152 so that when the forward end of the lever is depressed by the interlock pin 31, the rear end of the lever 150 extends between the forks of the bifurcated end of an arm 153 of a yoke 154, which is rotatably supported on a horizontal pin 155 anchored directly to the wall member 51 (Fig. 1). The other arm of the yoke 154 extends upwardly and constitutes the latch 149, previously referred to.

When the forward end of the lever 150 is depressed by the interlock pin 31 of the postage meter (as it is when the machine is in proper operative condition), the rear end of the lever 150 is elevated to rock the latch 149 clear of the end of the arm 110, as shown in full lines in Fig. 5, so that the latch lever 99 can be actuated by the solenoid 135 to engage the clutch. On the other hand, if the postage meter is not properly placed on the power unit, or if the interlock pin 31 of the postage meter has been retracted, due to any one of several conditions rendering the postage meter inoperative, then the front end of the lever 150 will be elevated and the rear end will be depressed to engage the latch 149 with the arm 110 of the latch lever and prevent engagement of the clutch.

The front end of the lever 150 is positively elevated by a mechanism actuated by the arm 34, that locks the postage meter in position when the arm is in releasing position. This mechanism is fully disclosed in our copending application Serial No. 364,052, filed November 2, 1940,

and will therefore not be described in detail herein.

Electrical circuit

Referring to the circuit diagram of Fig. 12, the motor 58 is shown connected by the mercury switch 119 directly across a supply line 156, so that it is energized each time the mercury switch 119 is actuated. This constitutes the only energizing circuit for the motor during intermittent operation. However, to permit continuous operation of the motor, which is desirable when a large amount of material is to be run through the machine, a separate manually operated switch 157 is connected in shunt to the mercury switch 119. When the manual switch 157 is closed, the motor is always energized, irrespective of the position of the mercury switch 119.

The solenoid 135 is connected to the supply line 156 through a switch 158, which switch is adapted to be operated by either of two different mechanisms, to be described later. A condenser 159 is connected across the switch 158 to reduce arcing at the contacts.

The switch 158 is shown as of a well-known type (Figs. 16 and 21) consisting of a case 160 having a pair of mounting bolts 161 and 162 projecting therefrom. The bolt 162 projects through a hole in the carriage wall 43 (Fig. 1) and the bolt 161 projects through a slot 163 in the same wall to permit a limited adjusting movement of the switch case. The switch mechanism proper is contained within the case 160 and is actuated by a plunger 164 projecting from the case. A leaf spring element 165 overlies the plunger 164 and is depressed to close the switch through the plunger 164 by mechanisms to be described. To facilitate accurate adjustment of the position of the switch relative to the actuating mechanisms therefor, an adjusting bolt 166 is provided in an ear 167 turned out from the plate 43. The leaf spring 165 is depressed to close the switch by pressure thereagainst of a lobe 168 on an arm 169, which is supported for swinging movement on a shaft 170 (Fig. 1) extending between the side plates 42 and 43 of the platen carriage, previously referred to.

The arm 169 is normally urged counterclockwise, by a tension spring 189, against a stop pin 190, but can be rocked clockwise to close the switch by either of two different mechanisms, one of which functions when the machine is being used to stamp envelopes and the other of which is used when the machine is being used to stamp tape.

Mechanism for actuating the control switch in response to insertion of envelopes

When the machine is set for the stamping of envelopes, or the like, (that may be manually fed into the machine) the printing head 35, the platen 38 and the associated mechanism, are in the condition shown in Fig. 13. This view shows an envelope 37 supported on a table 171 and which is being pushed into the machine in the direction indicated by the arrow—(from right to left in Fig. 13). Positioned in the path of the envelope 37 is a trigger 172 which constitutes the upper end of a lever 173 fulcrumed on a stub shaft 174 on the plate 43 (Fig. 13). The lever 173 is urged clockwise by a light tension spring 175, and its clockwise movement is limited by contact of an ear 176 against the bottom of a notch 177 in a disc 178 (Fig. 13) secured to the shaft 39 which supports and drives the platen 38, so that the disc rotates with the platen.

When the forward edge of the envelope 37 reaches the trigger 172, it rocks the lever 173 counterclockwise. Initial rocking movement of the lever carries a pin 179 thereon against the shoulder 180 on an arm 181 fulcrumed at 182 to the arm 169. The arm 181 is normally held against a stop 191 on arm 169 by a tension spring 188 stretched between the arm 181 and a stationary post 192. Further movement of lever 173 into the position shown in Fig. 14 imparts downward movement to the arm 181, and rocks the arm 169 clockwise to depress the switch spring 165 and close the switch.

Closure of the switch energizes the solenoid 158 to engage the clutch, as previously described, and rotate the platen and the printing head.

Initial rotation of the platen and the disc 178 carries the notch 177 in the disc clear of the ear 176, so that during the remainder of the cycle the unbroken portion of the rim of the disc prevents return of the lever 173 back to normal position.

Downward movement of the arm 169 (Fig. 14) is limited by engagement of a surface 169a thereon against a hub 183 on the lever 173, which in turn limits counterclockwise movement of the lever 173 in response to pressure exerted against the trigger 172 by the envelope 37. The trigger 172 therefore functions as a stop to hold the envelope in a predetermined position for engagement by the printing head and platen so that the postage will always be imprinted on the envelope in a desired, longitudinal position.

With the parts in the position shown in Fig. 14, the platen 38 rotates counter-clockwise until a lug 184 pressed out from a disc 185 on the platen shaft 39 reaches the upper end of the arm 181 and rocks the arm clockwise sufficiently to carry the shoulder 180 clear of the pin 179. Immediately thereafter, a cam shoulder 186 on the disc 178 reaches the lug 176 (Fig. 15) on lever 173 and cams the lever further counter-clockwise into the position shown in Fig. 15 and holds it in that position throughout the remainder of the cycle. The additional counter-clockwise movement of the lever 173 carries the pin 179 past the shoulder 180 into the path of a second shoulder 187 on the arm 181 to block return of the latter in response to the force of a tension spring 188, after the lug 184 has moved past the upper end of arm 181.

The movement of the shoulder 180 clear of the pin 179, permits the tension spring 189 to rock the lever 169 counter-clockwise back into its normal position, resting against the stop pin 190, this movement carrying the arm 181 upwardly so that the shoulder 187 thereon is juxtaposed to the pin 179.

With the apparatus in the position shown in Fig. 15, the leading end of the envelope 37 is being engaged between the printing surface 36 of the printing head 35 and the pressure face of the platen 38, so that continued rotation of the printing head and the platen carries the envelope therebetween and imprints the postage thereon in so doing. The switch-actuating mechanism remains in the position shown in Fig. 15 until the end of the cycle, at which time the lug 176 again drops into the notch 177 in the disc 178, permitting retraction of the lever 173 by its tension spring 175 back into the normal position shown in Fig. 13. Upon this return movement of the arm 173, the pin 179 therein snaps past the corner formed by the two shoulders 180 and 187 on the arm 181, permitting re-

traction of the arm 181 by its spring 188 against its stop pin 191.

Since the switch 158 was opened prior to the completion of the cycle, the clutch is disengaged at the end of the cycle by the arm 100 (Fig. 5) on the latch lever 99 and the machine will remain in normal position until the solenoid is again energized by movement of another envelope (Fig. 13) against the trigger 172, when the machine will be actuated as described to operate through one cycle, and print postage on the envelope as it is fed therethrough.

As the envelopes leave the printing head and platen they are delivered between the discharge roller 73 (Figs. 1 and 24) and an idler roller 193 and they are discharged from the machine by the driving action of the roller 73. It is desirable that the discharge roller 73 continue to rotate for an appreciable interval of time following completion of a cycle of operation of the printing head and platen, to insure that long envelopes will be completely discharged. It is for this reason that the discharge roller 73 is positively driven from the electric motor 58 independently of the clutch that couples the driving motor to the printing head and platen. When the machine is being operated intermittently, the motor switch is opened at the same time that the clutch is disengaged to stop the printing head and platen, but whereas the printing head and platen are stopped immediately by the disengagement of the clutch, the electric motor continues to rotate by virtue of its momentum, thereby continuing the rotation of the discharge roller for a sufficient length of time following completion of the printing cycle to discharge the longest envelope from the machine.

Mechanism for actuating the control switch when printing on tape

When it is desired to print postage on tape, instead of on envelopes and the like, the envelope-actuated trigger 172 and the discharge roller 73 are swung out of the way, and a tape-handling mechanism is swung into position to feed tape between the printing head and platen. When adjusted to print on tape, the machine is started by manually depressing a push button 195 (Figs. 1 and 24) which push button is mounted on a plunger 196 (Fig. 14) supported in a guide bracket 197 and is normally maintained in outer position by a compression spring 198. Depression of the push button 195 operates through a linkage to close the switch 158 and energize the solenoid to start a printing cycle.

Thus the inner end of the plunger 196 (Fig. 13) bears against the upper end of an arm 199 which is secured to a sleeve 200 rotatably supported on the shaft 210. The arm 199 is normally urged counter-clockwise against the plunger 196 by a light tension spring 201, and has a shoulder 202 overlying an ear 203 on the arm 181, so that depression of the plunger 196 causes the shoulder 202 to engage the ear 203 on the arm 181 and rock it and the arm 169 downward to close the switch 158 in the manner previously described.

However, when the machine is adjusted for printing on envelopes, as shown in Fig. 13, movement of the arm 199 to engage the shoulder 202 thereon against the ear 203 is prevented by a locking mechanism. This locking mechanism includes an arm 204 projecting downwardly and to the right (as viewed in Fig. 13), which arm is fastened to the same sleeve 200 that the arm

199 is fastened to, and the arm 204 extends between a pair of pins 205 and 206 on a frame member 207 of a tape chute 208. The pins 205 and 206 prevent rocking movement of the arm and 204, which in turn prevents movement of the arm 199 in response to force transmitted thereto by the plunger 196 from the push button. It will be apparent, therefore, that while the machine is conditioned for printing on envelopes, it is impossible to energize the clutch solenoid with the push button 195.

The tape-handling chute 208 is supported on rear and front frame members 207 and 209, respectively, which rotate on a shaft 210 which extends between the platen carriage frame plates 42 and 43 (Fig. 1).

The machine is adjusted to print on tape instead of on envelopes, by rocking a control arm 211 (Figs. 1 and 24) which swings the discharge roller downwardly out of the way and simultaneously rocks the tape chute 208 about the shaft 210 from the inactive position shown in Fig. 13 into the active position shown in Fig. 17. The mechanism for shifting the discharge roller and the tape chute in response to manual movement of the control arm 211 is fully described in our copending application Serial No. 369,570, and need not be described herein since an understanding of it is not essential to an understanding of the present invention.

Initial counter-clockwise movement of the tape chute 208 out of the inactive position shown in Fig. 13, positively locks the switch-actuating mechanism against operation. Thus there is secured to the tape chute frame plate 207, for rotary movement therewith, a collar 212 having an ear 213 which is normally positioned just to the right of a downwardly extending finger 214 on the arm 169, so as to permit downward movement of the arm to actuate the switch in the manner previously described. However, the initial movement of the tape chute 208 counter-clockwise carries the ear 213 into the path of the finger 214 (Fig. 16) to prevent downward movement of the arm 169, and it remains in position to block the finger 214 until the tape chute has completed its movement into the position shown in Fig. 17, (which movement carries the ear 213 past the finger 214). By the time the tape chute has been moved into operative position (Fig. 17), the envelope trigger 172 has been moved out of the way and rendered inoperative to actuate the switch 158, so that the latter is then under the sole control of the plunger 196.

The envelope trigger 172 is shifted out of the way by the nose of the tape chute in response to movement of the tape chute into operative position, the mechanism coupling the trigger to the switch being disabled to permit the movement. In this connection, it will be recalled that when the mechanism is in condition for stamping envelopes, movement of the trigger 172 (Fig. 13) by an envelope, rocks the trigger lever 173 to carry the pin 179 thereon against the shoulder 180 on the arm 181, depressing the latter and the switch-actuating arm 169 on which the arm 181 is pivoted. However, movement of the trigger lever 172 by the nose of the tape chute 208 cannot actuate the switch because before the nose of the chute reaches the envelope trigger, the pin 206 on the chute frame cams a tail 215 (Fig. 16) on the arm 181 downwardly, rocking the shoulder 180 clear of the path of the pin 179, while the trigger lever 173 is being rocked into the position shown in Fig. 17. Final movement

of the tape chute 208 into operative position carries the pin 206 past the cam surface 216 on the tail 215 of arm 181, permitting the latter to be retracted by its tension spring 188 back into normal position in which the ear 203 is positioned below the shoulder 202 on the arm 199 (Fig. 17). Thereafter clockwise rocking movement of the arm 199 will carry the shoulder 202 thereon against the ear 203 and move the arm 181 downwardly, thereby rocking the arm 169 clockwise and causing the lobe 168 on the latter to close the switch 158 to energize the solenoid.

It will be observed from inspection of Fig. 17 that when the tape chute is in operative position the pin 205 thereon has been carried clear of the arm 204 so that it cannot prevent clockwise rocking movement of the arm 199 in response to pressure thereagainst by the plunger 196. However, an additional interlock is provided for preventing clockwise rocking movement of the arm 169 to close the switch 158, unless a tape is present in the tape chute.

Thus, the tape 217 upon which postage is to be printed extends into the lower end 218 of the chute (from a supply roll 217a, Fig. 1), thence through the chute between inner and outer peripheral walls 219 and 220, respectively, to the forward end 221 of the chute walls. When the tape mechanism is properly supplied with tape, the latter extends from one end to the other of the chute. An interlock mechanism is therefore provided for detecting the presence of the tape in both ends of the chute. This mechanism includes a bellcrank lever 222 fulcrumed at 223 near the rear end of the chute and having an arm 224 with a finger 225 thereon adapted to enter through juxtaposed apertures 226 in the chute walls 219 and 220. The other arm 227 of the bellcrank lever is connected by a link 228 to an arm 229 pivotally supported at 230 on the side frame member of the chute. Adjacent the forward end of the chute, there is mounted a lever 231 which is fulcrumed at 232 to the side of the chute and has a finger 233 adapted to enter a pair of juxtaposed apertures 234 in the inner and outer peripheral walls of the chute. This lever 231 is connected, by a link 235, to an arm 229a positioned alongside the arm 229 and supported on the same pivot 230. Both of the arms 229 and 229a are urged clockwise by tension springs 237 so that the fingers 225 and 233 are urged against the tape 217 in the opposite end portions of the chute. If tape is present in the chute at both ends, the fingers are restrained by the tape and the arms 229 and 229a are held in the position shown in Fig. 17, in which hooks 238 on the lower ends of the arms are clear of an ear 239 on the right end of the arm 169 so that the latter is not restrained by the arms 229 and 229a against downward movement to close the switch. However, if the chute is not filled with tape, then one or both of the fingers 225 and 233 can move through the adjacent apertures in the chute in response to the force of its associated spring 237 and engage one or both of the hooks 238 with the ear 239 to prevent downward movement of the arm 169. Fig. 20 shows the apparatus with no tape in the forward end of the chute and the finger 233 raised by its associated spring 237, this movement being accompanied by clockwise rotation of the arm 229a to carry the hook 238 thereon below the ear 239 and prevent closing of the switch. It will be observed that the arm 229 is in normal position in Fig. 20 because tape is present in the rear end of the chute juxtaposed to the finger 225.

It is desirable to lift the fingers 233 and 225 clear of the tape 217 during the printing operation so as to prevent unnecessary frictional resistance to movement of the tape through the chute, and to this end the arms 229 and 229a are provided with identical shoulders 240 juxtaposed to a recess 241 in a cam disc 242, which is mounted on the platen shaft 39 immediately in front of the disc 185 (Fig. 21). Initial rotation of the platen 10 and the cam disc 242 (Fig. 17) carries the recess 241 past the shoulder 240 forcing the latter outwardly and rocking the arms 229 and 229a counter-clockwise to lower the finger 233 and raise the finger 225 clear of the tape in the chute. At the completion of the cycle, the recess 241 is again juxtaposed to the shoulders 240, permitting the interlock mechanism to function to prevent closure of the starting switch if the chute is not filled with tape.

The machine, when adjusted to print on tape as shown in Fig. 17, is manually started by depressing the push button 195 and the plunger 196, 15 rocking the arm 199 clockwise to carry the shoulder 202 thereon against the ear 203 on the arm 181, which in turn depresses the arm 169 and causes the lobe 168 thereon to move the switch blade 165 into position to close the circuit to the solenoid, whereupon the motor is started and the clutch engaged in the manner previously described. The platen and printing head thereupon 20 rotate through a revolution to print on and deliver a section of tape in a manner which is fully described in our copending application Serial No. 369,570.

Special provision is made to stop the machine 25 at the end of the cycle, and prevent the machine from printing more than once in response to a single depression of the starting plunger. The mechanism for doing this includes an ear 243 on the arm 199, and the cam disc 185 on the platen shaft 39. When the machine is in neutral position, as shown in Fig. 17, the ear 243 is juxtaposed to a recessed portion 245 in the periphery of the cam disc 185, which permits sufficient 30 clockwise movement of the arm 199 to close the switch in the manner already described. However, as the platen rotates (in counterclockwise direction), the rising portion of the cam disc bears against the ear 243 and forces the arm 199 sufficiently to open the switch contacts 158 but not sufficiently to disengage the shoulder 202 from the ear 203. Furthermore, at substantially the time when the concentric portion 246 of the cam disc reaches the ear 243, the lug 184 on the 35 cam disc 185 engages the upper end of the arm 181, rocking it clockwise to carry the ear 203 thereon, out from below the shoulder 202 on the arm 199, so that after the lug 184 has passed the arm 181 and the latter is restored by its tension spring 188, the ear 203 lies against the end 248 of shoulder 202, instead of therebelow, permitting the arm 169 to be restored into full open-switch position by its tension spring 189. This leaves the switch open so that the solenoid 40 is deenergized and the machine will not be started at the end of the cycle, even though the operator maintains pressure constantly on the starting button. However, if the operator then releases the starting button, permitting the arm 199 to be rocked back into normal position by its spring 201, the end 248 of the shoulder 202 is carried clear of the ear 203 on the arm 176, permitting the latter to be restored into normal position by its spring 188, so that the next time 45 the starting button is depressed, the shoulder 202

78

on arm 199 will engage the ear 203 and close the starting switch exactly as previously described.

Fig. 18 shows the mechanism at the instant of starting, when the starting button is fully depressed, and Fig. 19 shows the mechanism approximately one-third way through the cycle, with the starting button still held down by the operator, to illustrate how the arm 181 is taken out of the control of the arm 199 by the lug 184 in the disc 185, to thereby prevent continuous operation of the machine through more than one cycle, irrespective of whether or not the operator takes his finger off the starting button after actuating it.

Although for the purpose of explaining the invention a specific embodiment thereof has been described in substantial detail, it is to be understood that various changes may be made in the particular construction shown without departing from the invention, which is to be limited only to the extent set forth in the appended claim.

We claim:

In a mail treating machine wherein a cyclically operable printing mechanism including a rotatable printing head is mounted on a power unit

adapted to drive the printing head, the combination of a platen rotatably mounted in said power unit adjacent said printing head and adapted with said printing head to feed an object therefrom and print on it, ejector roller means for receiving objects from said printing head and platen and ejecting them from the machine, an electric motor in said power unit for driving said printing head, said platen and said ejector roller, means permanently coupling said ejector roller to said motor for operation with said motor at all times, clutch means for selectively connecting said printing head and platen to said motor to begin a cycle of operation thereof and for disconnecting it at the end of a cycle to stop the printing head and platen, and control means for closing and opening the motor circuit substantially simultaneously with engagement and disengagement respectively of said clutch, the movable elements of said motor and ejector roller having substantial inertia whereby they continue in motion for an appreciable interval of time following the completion of the cyclical movement of the printing head and platen.

25 COMMODORE D. RYAN.
EDWARD P. DRAKE.
